UNITED STATES PATENT OFFICE.

GEORGE HAMILTON VANDERSLICE, OF INDIANAPOLIS, INDIANA, ASSIGNOR TO ZENITE METAL COMPANY, OF INDIANAPOLIS, INDIANA, A CORPORATION OF INDIANA.

DESIGN FOR A SINGLE-BEAD MOLDING OR WELT.

56,716.

Specification for Design.

Patented Nov. 30, 1920.

Application filed April 8, 1918. Serial No. 227,383. Term of patent 14 years.

To all whom it may concern:

Be it known that I, GEORGE HAMILTON VANDERSLICE, a citizen of the United States, residing at Indianapolis, in the county of Marion and State of Indiana, have invented a new, original, and ornamental Design for a Single-Bead Molding or Welt, of which the following is a specification, reference being had to the accompanying drawing, forming part thereof.

The single figure of the drawing is a

fragmentary perspective view of a single bead molding or welt, showing my new design.

I claim:—

The ornamental design for a single bead molding or welt, as shown.

In witness whereof I have hereunto set my hand at Indianapolis, Indiana, this fourth day of April, A. D. one thousand nine hundred and eighteen.

GEORGE HAMILTON VANDERSLICE.
